J. W. RICH

GAME POUCH

Filed Dec. 29, 1927

Inventor
John W. Rich,

By Clarence O'Brien, Attorney

UNITED STATES PATENT OFFICE.

JOHN WOODS RICH, OF WOOLRICH, PENNSYLVANIA.

GAME POUCH.

Application filed December 29, 1927. Serial No. 243,256.

The present invention relates to improved game pouch of the type adapted to be removably placed in a pocket, such as is ordinarily found on the back of a hunter's coat, and the purpose of the invention is to provide a bodily removable pouch, such as may be readily placed in or removed from the open ended pocket in the coat.

As is well known the ordinary hunter's coat is provided with a pocket for the carrying of game. In carrying the game in the pocket however, the same becomes blood-soaked, and very untidy. Moreover it is very inconvenient to wash the pocket or the coat, and in view of these objections, I have evolved and produced a novel pouch which can be placed in the pocket for carrying the game in the pouch.

My principal aim is to provide a simple and inexpensive pouch which is constructed of blood and water-proof material, such as renders the pouch very efficient for the carrying of game and permits it to be removed for washing to maintain it in a sanitary condition.

More specifically speaking, I propose the production of a removable pouch for insertion in a coat pocket, wherein this pouch is lined with water-proof material, and wherein it is provided with entrance openings on opposite edges to be alined with the entrance openings of the pockets, whereby to facilitate insertion of the game.

Another feature of the pouch, is that it is constructed to permit it to be temporarily fastened to the coat to prevent accidental displacement.

Other features will become apparent from the following description and drawings.

In the drawings:—

Figure 1 is a view of a fragmentary portion of a hunter's coat with the pocket on the back thereof containing the improved pouch.

Fig. 2 is a horizontal section through the pocket and pouch.

Fig. 3 is a vertical section through the same.

Fig. 4 is a detail view of the pouch removed from the pocket.

Referring now to the drawings by numerals, it will be seen that the coat is generally designated by the reference character 5, and, as is usual, it is provided on the back

with an open ended pocket 6 in which the game is ordinarily placed. However, as before stated, the coat thus constructed, has several disadvantages which are overcome by the present invention.

In carrying out the present invention, an improved pouch, generally designated by the reference character 7, is provided.

The pouch is composed of two plies of material fixed together, thus closing the bottom edge as shown at 8 and closing the top edge 9. Along the top edge we find snap fasteners or equivalent separable fasteners 10 which will cooperate with complementary fasteners inside of the coat pocket, thus permitting the pouch to be temporarily and effectively fastened within the coat pocket.

Along the opposite edges as shown at 11 in Fig. 4, the two pieces of material are stitched together, up to a predetermined point. Then the remainder of the edge portions are left open to provide a mouth 12 on each side. These mouth portions aline with the entrances of the coat pocket, and aid in the placement of the game thru the pocket entrances and into the pouch.

The pouch is also provided with tabs 13 having button holes to connect with the usual buttons 14 fastened to the coat in the manner shown in Fig. 1.

This aids in the maintenance of the pouch. However, the pouch can be readily removed, whenever desired or necessary to permit it to be washed, and to keep it in a sanitary condition.

From the foregoing description and drawings, it will be seen that I have evolved and produced an efficient game pouch capable of being used in association with the pocket of a hunter's coat, without requiring alterations of any of the existing details. It adds to the practicability of the coat and is supplemental, thus permitting it to be used when desired, and entirely removed when desired.

The device is economical and characterized by an arrangement of details, which make it practical and efficient for the purposes for which it has been designed. The description taken in connection with the drawings, will permit a clear understanding of the invention to be had. Therefore, a more lengthy description is regarded unnecessary.

Having thus described my invention, what I claim as new is:—

As a new product of manufacture, a game pouch ~~for use in association with a hunter's coat pocket~~, said pouch being composed of two thicknesses of material connected together along the top and bottom edges, and stitched along their remaining side edges up

to a predetermined point, forming entrance mouths on opposite sides, said pouch being constructed of substantially water-proof material, and being equipped with apertured tabs and fastening means whereby it may be separably connected with a coat.

In testimony whereof I affix my signature.

JOHN WOODS RICH.
